CLAIM

I claim the ornamental design for a drinking bottle cap with trapezoidal lid, as shown and described.

DESCRIPTION

FIG. 1 is a front perspective view of the drinking bottle cap with trapezoidal lid;

FIG. 2 is a rear perspective view of the drinking bottle cap with trapezoidal lid;

FIG. 3 is a side elevational view of the drinking bottle cap with trapezoidal lid;

FIG. 4 is a side elevational view of the opposed side of the drinking bottle cap with trapezoidal lid;

FIG. 5 is a front elevational view of the drinking bottle cap with trapezoidal lid;

FIG. 6 is a rear elevational view of the drinking bottle cap with trapezoidal lid;

FIG. 7 is a top elevational view of the drinking bottle cap with trapezoidal lid; and,

FIG. 8 is a bottom elevational view of the drinking bottle cap with trapezoidal lid.

The broken lines in the drawings represent unclaimed environmental subject matter and form no part of the claim.
